UNITED STATES PATENT OFFICE

2,688,946

SHAFT ROTATION INDICATOR

François Jarsaillon, Lyon, France

Application August 29, 1950, Serial No. 181,987

Claims priority, application France
September 8, 1949

8 Claims. (Cl. 116—115)

1

The present invention relates to circulation-accelerators for central heatings and especially to heatings with hot-water pipes. It has for its chief object the provision of a device which will greatly accelerate the water circulation and which will considerably increase the heat-production of the boiler at a very low cost.

Another object of the invention is to provide an accelerator which will work without any lubrication smoothly, without any noise, and without any noteworthy wear.

The device according to the invention consists in the particular construction or arrangement of a pump directly connected to an electro-motor and is placed at the inlet or outlet of the boiler, where it accelerates the circulation of the water, which usually takes place by means of thermal siphonage.

The accelerator being directly coupled with the motor, having no stuffing-box and being constantly lubricated by a water-film, works without any noteworthy wear and without any noise. In case of the stoppage of the motor, the pump will present an insignificant resistance to the passage of the water, in spite of its excellent operating efficiency during normal working.

The accompanying drawing shows by way of example a constructional embodiment of the invention. In the drawing:

Figure 1 is a sectional view of an accelerator according to the invention;

Figure 2 is an enlarged sectional view of a detail of the combined indicating and control means in accordance with the present invention.

Figure 3 is a side view of Figure 2.

The accelerator shown in Figure 1 comprises a pump 1, connected by means of a flange 2 to an electro-motor, comprising a stator 3 and a rotor 4 which are separated from each other by a jacket 5 made of metal or plastics.

A shaft 6 which is provided with a longitudinal drain 7 and which is centered with some clearance between the bearings 8 and 9 of the flange 2 and the snout 10, couples the rotor 3 with the propeller or paddle-wheel 11 of the pump 1.

Between the flange 2 and the rotor 4 is provided a stop 12, one part of which consists of mobile jaws made of special bronze and the other part, adapted to the rotor, be made of stainless metal.

The snout 10 comprises holes 13 which allow the passage of a part of the water displaced by the pump 1, through the ducts 14 of the flange 2, and through the bearings 8 and 9. The drain 7 of the shaft 6 assures the reflux of the fluid,

2

traversing the bearing 8, and which then is reconducted through the openings 15 into the pump.

The bearings 8 and 9, as well as the stop 12, are thus permanently lubricated by a liquid-film derived from the heating water, brought hereafter by centrifugal action towards the propeller 11.

This arrangement produces exceptional reliability in service, due to the permanent presence of a water-film between the mobile and immobile parts which prevents any friction of metal upon metal, thus rendering amount of the wear negligible.

The jacket 5, adjusted between the stator 3 and the rotor 4, assures the fluid tightness of the apparatus and avoids the drawbacks of the usual stuffing-boxes, which considerably restricts the power of the motor.

The pump 1 is adapted not to oppose any resistance to the passage of the heating water in case the motor should stop. Its working output is, notwithstanding, very high.

Apart from their usual construction, the stator 3 and the rotor 4 may consist of an agglomerate of iron-powder and appropriate plastics. The rotor 4 may be of vacuum-die casted aluminium or copper. The windings of the stator 3 may be substituted by appropriately connected permanent magnets.

The plug connection being placed at the motor end in 28 greatly facilitates the mounting and connection thereof.

Since there is no friction between the turned parts and the bearings, the operation of the apparatus is absolutely noiseless.

The power consumption of the operating accelerator which increases considerably the circulation of the heating water is very low and whatever power is consumed is more than compensated by the considerable increase of the calorific output of the boiler, provided with such an accelerator.

The electro-motor may be replaced by a suitable turbine, fed by the water main, in a closed or open water system, in which case and in order to avoid the mixing of the water from the water main with the circulating heating water, a natural or artificial magnet is interposed between the shaft of both motor and propeller, forming thus a connection of the two shafts.

The accelerator may be used for fluids of all kinds, and may be driven by any appropriate means.

The operation of the circulation accelerator, to be described in greater detail hereinafter is so

quiet and smooth that it is impossible to ascertain whether the circulation accelerator is operating or not, unless a stethoscope-like instrument is used for acoustic examination or by tactile process, that is by touching the shaft directly or with suitable means. In accordance with the invention in order to determine whether the circulation accelerator is operating a combined indicating and operating means is used for visually indicating the direction of rotation of shaft when the latter is rotating and for turning the shaft when the latter is not rotating. The combined indicating and operating means is constituted of the following parts:

At the end of the case 1 of the accelerator and in the axis of its shaft a tapped projection 16 is provided, adapted to receive a guide comprising a threaded head 17 of a flange 18, overtapped by a threaded casing 19 which, in turn, is covered by a nut 20, tightened by means of a gasket 21. The boring of the guide is filled by a rod 22 of a screwdriver 23 which is pressed back against the head 17 and out of reach of the slit 27 at the end of the shaft of the motor propeller 11, by means of a spring 24 resting against the underside of bolt head 25.

In order to use the controller, the cap 20 is unscrewed and the screwdriver 23 pushed into the slit 27. In case of necessity should the shaft 6 of the pump jam or freeze due to non-use of the apparatus, as for instance during the summer period, when the central heating and thus water circulation is stopped, the shaft of the pump may be turned loose by means of a wrench acting upon the bolt 25. The direction of rotation is indicated by the bolt 25 which has an end shaped like a screw driver 23 in the casing, and the other end thereof visibly extending outside the casing 1. The direction of rotation can therefore be determined not only through tactile indications but visual indication as well, when the cap 20 is removed.

The emplacement of the rod 22 makes the bolt 25 easily attainable even in the vicinity of a wall or partition. When the cap 20 is being unscrewed only a few drops of the fluid will flow off; for that reason the emptying of the apparatus is avoided.

It is to be understood that the described accelerator may be modified in its constructional details in any appropriate manner within the scope of the invention.

Having described my invention, what I claim is:

1. A device for indicating the direction of revolution of a shaft means and for manually turning the same whenever required, comprising, in combination, a casing adapted to enclose at least one end of the shaft member, said casing formed with a bore arranged opposite said one end of the shaft member; elongated combined indicating and operating means having the same cross-section as said bore and arranged permanently and fluid-tightly in said bore, said elongated combined indicating and operating means being arranged with one end thereof located in said casing and the other end thereof permanently and visibly located outside of said casing, said elongated means being rotatable about its axis and movable along said axis between an inoperative position with said one end thereof spaced from said one end of said shaft, and an operative position when moved further into said casing and engaging with its said one end of said shaft means; engaging means on said one end of said shaft means and said one end of

said elongated combined indicating and operating means for engaging said shaft means, said combined indicating and operating means in said operative position thereof indicating the direction of said shaft when the latter is rotating and adapted for rotating said shaft when the same is not rotating and said elongated means for rotative movement with each other if one of said means is rotated; and means permanently urging said elongated combined indicating and operating means from said operative into said inoperative position, so that said indicating and operating means is actuated by pushing said elongated means at said other end thereof into said bore of said casing and into engagement with said one of said shaft means.

2. An arrangement of the character described, comprising, in combination, a casing having a bore; a shaft means arranged in said casing and having one end; means rotatably supporting said shaft means in said casing with said one end thereof arranged opposite said bore; elongated combined indicating and operating means having the same cross-section as said bore and arranged permanently and fluid-tightly in said bore, said elongated combined indicating and operating means being arranged with one end thereof located in said casing and the other end thereof permanently and visibly located outside of said casing, said elongated means being rotatable about its axis and movable along said axis between an inoperative position with said one end thereof spaced from said one end of said shaft, and an operative position when moved further into said casing and engaging with its said one end said one end of said shaft means, said combined indicating and operating means in said operating position thereof indicating the direction of rotation of said shaft when the latter is rotating and adapted for rotating said shaft when the latter is not rotating; engaging means on said one end of said shaft member and said one end of said elongated combined indicating and operating means for engaging said shaft means and said elongated means for rotative movement with each other if one of said means is rotated; and means permanently urging said elongated combined indicating and operating means from said operative into said inoperative position, so that said indicating and operating means is actuated by pushing said means at said other end thereof into said bore of said casing into engagement with said one end of said shaft means.

3. A device for indicating the direction of revolution of shaft means and for manually turning the same whenever required, comprising, in combination, a fluid-tight casing adapted to enclose at least one end of the shaft means, said casing formed with a bore arranged opposite said one end of the shaft member; an elongated combined indicating and operating means having the same cross-section as said bore and arranged permanently and fluid-tightly in said bore, said elongated combined indicating and operating means being arranged with one end thereof located in said casing and the other end thereof permanently and visibly located outside of said casing, said elongated means being rotatable about its axis and movable along said axis between an inoperative position with said one end thereof spaced from said one end of said shaft, and an operative position when moved further into said casing and engaging with its said one end said one end of said shaft means, said com-

5 bined indicating and operating means in said operative position thereof visually indicating the direction of said shaft when the latter is rotating and adapted for rotating said shaft when the same is not rotating; engaging means on said one end of said shaft member and said one end of said elongated combined indicating and operating means for engaging said shaft means and said elongated means for rotative movement with each other if one of said means is rotated; and means permanently urging said elongated combined indicating and operating means from said operative into said inoperative position, so that said indicating and operating means is actuated by pushing said means at said other end thereof into said bore of said casing into engagement with said one end of said shaft means.

4. A device for indicating the direction of revolution of shaft means and for manually turning said shaft means whenever required, comprising, in combination, a casing adapted to enclose at least one end of said shaft means, said casing formed with a bore arranged opposite said one end of said shaft means; a bolt serving as a combined indicating and operating means having the same cross-section as said bore and arranged permanently and fluid-tightly in said bore, said bolt serving as a combined indicating and operating means being arranged with one end thereof located in said casing and the other end thereof permanently and visibly located outside of said casing, and being rotatable about its axis and movable along said axis between an inoperative position with said one end thereof spaced from said one end of said shaft, and an operative position when moved farther into said casing and engaging with its said one end said one end of said shaft means, said combined indicating and operating means in said operative position thereof visually indicating the direction of said shaft when the latter is rotating and adapted for rotating said shaft when the same is not rotating; engaging means on said one end of said shaft means and said one end of said bolt serving as a combined indicating and operating means for engaging said shaft means and said bolt member for rotative movement with each other if one of said means is rotated; and means permanently urging said bolt serving as a combined indicating and operating means from said operative into said inoperative position, so that said indicating and operating means is actuated by pushing said means at said other end thereof into said bore of said casing into engagement with said one end of said shaft means.

5. An arrangement of the character described, comprising, in combination, a fluid-tight casing having a bore; shaft means arranged in said casing and having one end; means rotatably supporting said shaft means in said casing with said one end thereof arranged opposite said bore; an elongated combined indicating and operating means having the same cross-section as said bore and arranged permanently and fluid tightly in said bore, said elongated combined indicating and operating means being arranged with one end thereof located in said casing and the other end thereof permanently and visibly located outside of said casing, and being rotatable about its axis and movable along said axis between an inoperative position with said one end thereof spaced from said one end of said shaft, and an operative position when moved further into said casing and engaging with its said one end said

5 one end of said shaft means, said combined indicating and operating means in said operating position thereof indicating the direction of rotation of said shaft when the latter is rotating and adapted for rotating said shaft when the latter is not rotating; engaging means on said one end of said shaft means and said one end of said elongated combined indicating and operating means for engaging said shaft member and said elongated means for rotative movement with each other if one of said means is rotated; and means permanently urging said elongated combined indicating and operating means from said operative into said inoperative position, so that said indicating and operating means is actuated by pushing said means at said other end thereof into said bore of said casing into engagement with said one end of said shaft means.

6. An arrangement of the character described, 20 comprising, in combination, a casing having a bore; shaft means arranged in said casing and having one end; means rotatably supporting said shaft means in said casing with said one end thereof arranged opposite said bore; a bolt serving 25 as a combined indicating and operating means having the same cross-section as said bore and arranged permanently and fluid tightly in said bore, said bolt serving as a combined indicating and operating means being arranged with one end thereof located in said casing and the other end thereof permanently and visibly located outside of said casing, and being rotatable about its axis and movable along said axis between an inoperative position with said one end thereof spaced from said one end of said shaft, and an 30 operative position when moved further into said casing and engaging with its said one end said one end of said shaft means, said combined indicating and operating means in said operating 35 position thereof indicating the direction of rotation of said shaft when the latter is rotating and adapted for rotating said shaft when the latter is not rotating; engaging means on said one end of said shaft means and said one end 40 of said bolt serving as a combined indicating and operating means for engaging said shaft means and said bolt member for rotative movement with each other if one of said means is rotated; and means permanently urging said bolt 45 serving as a combined indicating and operating means from said operative into said inoperative position, so that said indicating and operating means is actuated by pushing said means at said other end thereof into said bore of said casing 50 into engagement with said one end of said shaft means.

7. An arrangement of the character described, 60 comprising, in combination, a casing having a bore; shaft means arranged in said casing and having a recess at one end; means rotatably supporting said shaft means in said casing with said one end thereof arranged opposite said bore; a bolt serving as a combined indicating and operating means having the same cross-section as said bore and arranged permanently and fluid tightly in said bore, said bolt serving as a combined indicating and operating means being arranged with an extension located in said casing and the other end thereof visibly and permanently located outside of said casing, and rotatable about its axis and movable along said axis between an inoperative position with said one end thereof spaced from said one end of said shaft, and an operative position when moved further into said casing and engaging with said

extension of said bolt said recess in said one end of said shaft for engaging said shaft member and said bolt member for rotative movement with each other if one of said members is rotated; and means permanently urging said bolt serving as a combined indicating and operating means from said operative into said inoperative position, so that said indicating and operating means is actuated by pushing said means at said other end thereof into said bore of said casing whereby said extension of said bolt member engages said recess in said shaft means.

8. An arrangement of the character described comprising, in combination, a fluid-tight casing having a bore; a shaft means arranged in said casing and having a recess at one end thereof; means rotatably supporting said shaft means in said casing with said one end thereof arranged opposite said bore; a bolt serving as a combined indicating and operating means having the same cross-section as said bore and arranged permanently and fluid tightly in said bore, said bolt serving as a combined indicating and operating means being arranged with an extension located in said casing and the other end thereof permanently and visibly located outside of said casing, and being rotatable about its axis and movable along said axis between an inoperative position

10

5 with said one end thereof spaced from said one end of said shaft, and an operative position when moved farther into said casing for engaging said extension of said bolt with the recess in said one end of said shaft means for rotative movement with each other if one of said members is rotated; resilient means permanently urging said bolt serving as a combined indicating and operating means from said operative into said inoperative position, so that said indicating and operating means is actuated by pushing said means at said other end thereof into said bore formed in said casing whereby said extension of said bolt means engages said recess in said shaft means; and a removable cap arranged on the outside of said casing, said cap enclosing part of said bolt.
